UNITED STATES PATENT OFFICE.

THOMAS WALTON, OF LONDON, ENGLAND.

APPARATUS FOR PRINTING AND COPYING MUSIC AND THE LIKE.

Application filed November 9, 1921, Serial No. 514,046, and in Great Britain November 9, 1920.

This invention relates to the printing or copying of music and like manuscript including the printing of any necessary letter-press and has for its object to provide a 5 simple, cheap and efficient form of apparatus by which such copying or printing may be readily and rapidly effected by hand.

The invention consists in apparatus for printing or copying music or the like comprising in combination means for holding and positioning the paper or other material to be printed on, means for selecting any particular type from a type magazine or holder and conveying such selected type to 10 the printing position and means for moving the selected type relatively to the paper or the like.

The invention also consists in apparatus of the above character having key-operated 20 means for selecting and manipulating the type.

The invention also consists in apparatus of the above character in which the type magazine or holder is movable relatively to the 25 selecting device to enable any particular type to be selected for conveyance to the printing position.

The invention also consists in other details 30 and arrangements hereinafter described or indicated.

My invention will now be described with reference to the accompanying drawings, in which:—

Figure 1 is a plan view of the apparatus; 35 Figure 2 is a transverse section on the line 2—2 of Figure 1;

Fig. 2^a shows an enlarged scale an end and side view of a part shown in Figs. 1 and 2;

40 Figures 3 and 4 illustrate a plan and front elevation respectively of a detail;

Figure 5 shows a detail of part of the device illustrated in Figure 1;

Figure 6 illustrates a modification of a 45 detail similar to Figure 3;

Figure 7 shows a further modification of a detail similar to Figure 3;

Figure 8 shows a view partly in section of a 50 modification of the type actuating device;

55 Figures 9 and 10 illustrate a plan view and section respectively of the modification of the type tray shown in Figure 7;

Figure 11 illustrates three views of the printing type bar;

Figure 12 is a side elevation of a detail 55 shown in Figure 1;

Figure 13 is a plan view of Figure 12;

Figures 14 and 15 show a side view and plan respectively of a modification of the arrangement shown in Figures 12 and 13; 60

Figure 16 shows a fragmentary sectional view of a modification;

Figure 17 is a front elevation of same, and

Figure 18 illustrates a further modification. 65

Figs. 19 and 20 show in plan and side elevation respectively a modification of the carriage traversing gear.

Figs. 21 and 22 show two forms of type locking device. 70

Referring now to the drawings in which like reference numerals indicate like parts in all the figures, I provide my improved apparatus with a base plate 1, having suitably located brackets 2 arranged to support 75 a carriage 3 provided with segmentally formed members 4 adapted to support the material to be printed upon.

The carriage 3 is further provided with arms 5 and 6 between which is located an 80 anvil strip 7 pivotally mounted to the arms 5 and 6, the strip 7 being capable of limited rotary movement within the limits of the two stops 8 and 9. The segmental members 4 are fixedly mounted on a spindle 10 provided 85 with suitable bearings 11 and 12 attached to the carriage 3. A tail piece 14 rigidly mounted upon the spindle 10 functions with the member 18 engaging in a suitable slide 20 adapted to move within the guides 23 and 90 20 to be operated by means of a lever 24, link 25, bell-crank 26 and link 27 whereby the operation of the lever 24 will cause the slide 20 to function within the guides 23 by which means the segmental members 4 carrying the material to be printed upon will assume any predetermined vertical position relatively to the printing means. 95

Handles 10^a may also be provided to be operated directly by hand to adjust the vertical position of the segmental members 4. 100

The carriage 3 is further adapted to be laterally spaced by means of suitable mechanism (see also Figure 5) comprising a rack 28 provided upon the lower edge of the extension 30 of the carriage 3 adapted to be moved in the direction of the arrow 28^x under the action of a spring (not shown) the 105

movement being controlled and regulated by means of a rocking plate 32 pivoted at 33 to the base plate 1 of the apparatus and adapted to oscillate thereon, a spring 34 being provided, to normally retain the rocking plate in the position shown.

The rocking plate 32 is provided with a fixed pawl 35 and a sliding pawl 36 moving in a groove 37 provided in the rocking plate 32 against the action of a spring 38^a, a stop 40, adapted to limit the movement of the sliding pawl 36 being also provided, the arrangement being such that on the rocking plate 32 being oscillated by means of the rod 42 the fixed pawl 35 is first withdrawn from engagement with the rack plate 28, the sliding pawl 36 thereupon coming into engagement therewith and moving with the rack plate 28 until stopped by the end of the groove 37. By this means it will be seen that by changing the position of the stop 40 relatively to the groove 37 the rack plate 28 can be moved through a definite predetermined distance whereby corresponding lateral movement is imparted to the carriage 3 through the rack 28, in conjunction with the spring (not shown), back spacing of the carriage being effected against the action of the spring by means of the pawl 43 pivoted upon the arm 44, which is in turn pivoted at 45 to a fixed part of the base plate 1, and operated by any suitable manually actuated link or other mechanism.

The type bars (Figure 1) are arranged in grooves provided in the segmental tray 50 pivoted to the base plate 1 at 52 and adapted to be rotated a definite distance according to the particular type which may be required, the arrangement being such that by pressure upon any one of the keys 53 each and all of which are carried upon levers 55 pivoted to the spindle 56, the type in the segmental tray 50 corresponding to that indicated on the face of the key is adapted to be brought into a definite operative position relatively to the printing member 58.

For this purpose the various keys and their corresponding levers are adapted to be depressed through a definite uniform distance by which means one or the other of the tracker bar 54 is correspondingly depressed about its pivot 57 a distance dependent upon the relative position of the key lever 55, it being obvious that the tracker bar 54 will be depressed to a greater degree the nearer the key levers are to the tracker bar pivot. The ends of the two tracker bars 54 are provided with inclined faces or cam members 60 adapted to operate a lever 61 pivoted at 63 carrying the type tray 50, the lever 61 being provided with a fork 64 engaging a pin 65 provided on the arm 62 for the purpose.

In a modification shown in Figure 6 the inclined faces or cam members 60 are adapt-

ed to operate a member 68 pivoted at a point 69 forming the centre of oscillation of a toothed segment 70 which in turn operates the pinion 71 to rotate the circular member 72 carrying the necessary type, it being obvious that a segmental type tray may be substituted for the circular member if desirable, the gear ratio between segment 70 and the pinion 71 being modified accordingly.

A printing arm or member 58 pivoted at 72 is adapted to engage and grip the type 73 when the latter has been brought into printing relationship therewith; the arcuate movement of the member causing a pin 75 attached to the sleeve 74^a to move forward in the cam groove 76 whereby the lip 77 will be caused to grip the edge 78 of the type while the latter is being raised into the printing position.

The printing arm or member 58 operates by depressing the printing key 79 against the action of a spring 80 whereby the link 81 and its extension 82 will cause the wedge or cam member 83 (see Fig. 2^a) working in a sliding member 84 to engage the tail piece 85 of the printing member 58, continued forward movement of the wedge member 83 causing its inclined face to depress the tail piece 85 whereby the printing arm or member 58 will raise the type 73 into printing relationship with the anvil strip 7 supporting the material to be printed upon.

If desirable the type bar may comprise three characters whose relative positions are indicated at 86, 87 and 88 (Fig. 11) in which case it will be necessary to alter the position of the pivot 72 of the printing member 58 by means of the handle 89 operating through links 90 and 91 to depress or raise the pivot 72 whereby the desired type may be brought into printing relationship with the anvil 7.

Inking rollers are also provided, operated from the printing mechanism through suitable linkwork, and adapted to be returned to their normal position under the influence of a spring.

A stave line printing wheel 50^a is also shown in Figures 1 and 2, mounted upon a pillar 51^a and provided with inking rollers 52^a, said wheel and its inking rollers being adapted to be swung into and out of its operative position by means of the handle 53^a.

In the modification of the printing means as shown in Figure 8 the printing key 79 is operated to depress a pivoted lever 96 whereby the arm 97 of a member pivoted at 98 is adapted to be raised and its extension 99 correspondingly depressed by which means the tail piece 95 of the printing member functions to grip the selected type and raise the same into printing relationship with the material upon the anvil strip 7. In this case also the type is shown in three rows and the

fulcrum of the printing member is adapted to be raised or lowered into corresponding positions within the slot by means of the bell-crank lever 100 pivoted at 101 and operating the link 102.

In order that the carriage 3 and the material to be printed upon can be moved through definite predetermined vertical distances, suitable keys 103 (Figures 1, 12 and 13) are provided adapted to be depressed to operate the lever 115 pivoted at its extremity and provided at its other extremity with an inclined face or cam member 112 which functions to move the spring controlled sliding pin 114 provided at its outer extremity with a pivoted pawl 116, over a plate 108, said plate being arranged to slide over the ratchet wheel 109 through a definite, but varying distance, such distance being determined by the selected key operating through links 106 and 107 connected with the keys. It will be seen that the ratchet wheel 109 is thereby adapted to be rotated a distance which is regulated by the relative movement 25 of the pawl 116 and the plate 108 the relative movement of the two working parts being definitely determined by the particular key employed. The ratchet wheel 109 is mounted on a spindle 110 having at its outer 30 extremity a gear wheel 111 which is adapted to operate a rack member 117 attached to or pivoted upon the member 20.

Figs. 14 and 15 show a modification of this device in which the pawl member 116 masked by the moving plate 108 is adapted to directly operate the rack plate 117.

If found desirable, such a device may also operate to provide traversing or lateral movement to the carriage (see Figs. 19 and 20) by substituting a flat rack member 160 for the ratchet wheel, as in Figs. 14 and 15, having its outer extremity forked or formed in two parts 161 and 162 provided with suitable rack teeth adapted to gear with two 45 pinions 163 and 164 mounted upon the extremities of a fixed transverse spindle 165, the inner edges of the two pinions being formed with engaging right and left handed clutch members 166 and 167 provided upon 50 their inner faces. A worm wheel 170 of suitable pitch is mounted upon the spindle in a central position and fixed relatively thereto, the worm wheel being provided on its outer faces with clutch members 171 and 55 172, either of which is adapted to engage its clutch member upon its corresponding pinion. The ratchet teeth upon the clutch members are adapted to drive in opposite directions, sufficient movement being provided in 60 the pinions whereby either might be drawn into or out of engagement with its corresponding clutch member to drive the worm wheel 170 fixedly mounted upon the transverse spindle. The worm may be adapted 65 to engage with a rack member 174 formed

upon the base of the carriage 3 by which means the operation of a suitable key will cause the carriage to move laterally through a definite distance according to which key is employed, means being provided whereby 70 either pinion may be clutched to the worm wheel, and movement of the carriage in either direction thereby effected.

Figures 7, 9 and 10 show a modification of the type carrier in which the type carrying member comprises three superimposed tiers of type 117, 118, 119 in which the type are adapted to be brought into operative position in a manner similar to that already described. In this case however in addition 75 to the tracker bar member 54, to vertically locate the type upon any one tray a pivotally mounted forked arm 120 supporting the printing member 58 is adapted to be raised by means of a cam member 121 pivoted at a 80 point 122, for the purpose of bringing it to a correct lever to operate a particular type carrying tray.

A centrally located aperture 119^a is provided on the upper and intermediate type 85 trays through which the type operating member 58 is adapted to operate when removing a type bar from either of the two lower trays.

In a modification of the device shown 90 in Figures 16 and 17 the type are adapted to be carried upon the periphery of a drum 123 which is adapted to be rotated into a suitable position relatively to the printing member by means of segments 124, 125, 100 pivoted at points 126, 127 and adapted to be operated through a distance depending upon the key lever of the particular type or character to be employed, the segments being adapted to mesh with a pinion 130 mounted 105 on a spindle 131 provided with suitable brackets 132, 133 and adapted to carry the type drum 123.

In the construction shown, the type are 110 removably positioned in the drum 123 by means of pins 145 provided upon their lower surface and are each further provided with inwardly projecting tapered tongues 135 adapted to be gripped by the two jaw members 136 provided at the outer extremity of 115 the printing member.

In the operation of this modification the printing key 79 upon being depressed against the action of the spring 137 operates the crank member 138 and link member 139 120 to actuate the sleeve 140 pivoted and slidably mounted upon the pedestal 141, the outward movement of the sleeve 140 causing the projections on the jaw members 136 to engage corresponding dimples on the 125 tongues 135 of the type. Further movement of the link member 139 then withdraws the type 135 from the drum 123, the movement being continued to cause the sleeve 140 to further rotate about its pivot 130

and thereby cause the type 135 held in the jaws 136 to be brought into printing relationship with the paper.

In this construction the carriage is provided with means whereby the paper or other material to be printed upon may be fed or moved through a definite predetermined distance by means of suitably arranged stops 148, 149 provided at the extremities of cross bars and adapted to retain the paper or other material, the arrangement being such that the paper or other material to be printed upon is held between the two stops 148 and 149 and the serrated bar 149^a, the stop 149 being provided with a spring controlled pin adapted to engage the serrations upon the upper surface of the bar.

In the position of the clips as shown the paper would be stretched taut for printing upon; when however the paper is required to be moved, the movable stop and cross bar 149 is lifted and moved up to the stop 148, dropped, and brought forward, bringing so much of the paper with it.

As the stop may be fixed in any predetermined position, definite amounts of paper or other material can thus be moved.

In the arrangement shown in Figure 18 the type bars are located on a square section spindle 150 mounted upon bearings 151 and adapted to be operated by means of a hand-wheel 152 whereby the type bars may be rotated to ensure the particular row of type is in its correct position relatively to the jaw members 135 and 136 upon the printing member, the correct lateral position for the particular type bar required being ensured by sliding the type carriers 151 in an axial direction, the amount of lateral movement being controlled by the depression of tracker bars through the medium of the key levers as hereinbefore described. In this case the printing member is operated by means of a slide 152 provided with suitable rollers 153 whereby the jaws 136 may function to grip the type bar and raise it in its operative position. The drum 154 is provided with a strip 155 having a flat surface over which the material to be printed upon is positioned during the operation of printing; the drum 154 being further adapted to be raised into the three relative positions necessary when the three type characters are formed upon one type bar, said raising means comprising a lever 156 pivoted at 157 and connected to an extension of the cylinder support 158, stops 159 being provided on a member 160 for this purpose. This anvil strip 155 also ensures that the material is in a plane surface when in its printing position.

The drum is further provided upon its outer surface with a fixed or removable layer of vulcanite, rubber composition, card-

board or other suitable material adapted to facilitate the making of a clear printed impression upon the paper or like sheet; longitudinally extending members 176 and 177 being provided in the construction shown, 70 adapted to co-operate with clamps 178 upon the spindle 179 for the purpose of fixedly securing one end of the packing material, and a ratchet member 180 upon the other member adapted to be rotated for the purpose of tightening the other extremity of the packing material. 75

Furthermore vertical movement of the paper or like sheet may be effected by rotation of the drum 154 upon its axis, such rotation being effected in relation to an index and pointer 182 provided on the edge of the cylindrical surface, by any suitable intervening mechanism so that the drum may be rotated to a definite position corresponding to any particular line or space in the stave or leger lines upon which any particular note is to be printed. Such movement is effected, for example, by means of ratchets connected by pawls operated by bell-crank or other suitable linkage or arranged so as to operate the pawls while permitting of lateral movement of the cylinder, in the manner well known in typewriting machines. 90

In this form of construction the rows of type bars are each mounted in keyhole or slotted frames, two forms being shown in Figs. 21 and 22; these frames forming retaining means for the type bars when the type bars are not required in action. 95

As shown in Fig. 21, locking frames each comprise a plate or strip 170 provided with keyhole or slotted apertures 171 which are adapted to cooperate with holes in the type trays through which project pins provided on the bases of the types, longitudinal movement of the plate or strip relatively to the type tray against the action of a spring by means of a cam member 174 serving to unlock the types, when the type tray is in a position for use. 105

Fig. 22 shows an alternate form of locking device in which the type tray is provided with circular holes through which the type bar pins project, the said projections being in this case provided with necks or reduced portions which are adapted to be engaged or disengaged by a sliding plate of the form shown, the operation of the plate being similar to that of the previous example. 115

These locking devices may if necessary or desirable be used with either form of printing member gripping device illustrated and described. 120

It will be seen with such an arrangement I am able to produce a machine capable of employing a very large number of different types without necessarily multiplying the keys employed for actuating the same and 130

without making further undue complication of the machine.

It is to be understood however that the invention is not to be confined to the foregoing details of construction which are given by way of example only as it will be obvious that various modifications may be made within the scope of the invention and various mechanical equivalents employed to effect the necessary movements of the apparatus as may be found necessary to meet any particular practical requirements which the invention may be called on to fulfil.

Having now described my invention what I claim as new and desire to secure by Letters Patent is:—

1. Apparatus for printing or copying music or the like comprising in combination a magazine containing a plurality of types, a plurality of keys corresponding to said types and a pivoted lever for each of said keys upon which said keys are mounted, a pivoted lever arranged beneath the key levers and positioned substantially at right angles thereto, said key levers being adapted to be manually depressed through a definite predetermined distance to give a definite but varying deflection to the last mentioned pivoted lever, a pivoted printing member, an inclined cam member arranged at the extremity of the last mentioned pivoted lever, means actuated by said cam member for rotating the type magazine and adapted to move the type magazine through a definite and varying distance depending upon the key operated to bring the selected type into functional relationship with said pivoted printing member.

2. Apparatus according to claim 1 in which the pivoted printing member is combined with means such that the first movement of said member automatically causes the same to positively engage a selected type for removal from the magazine.

3. Apparatus according to claim 1 in which the pivoted printing member is provided with cam operated means for gripping a selected type for removal from the magazine.

4. Apparatus according to claim 1 in which the pivoted printing member is provided

with gripping means comprising jaws adapted to co-operate with suitable extensions provided upon the type for the purpose of removing a selected type from the magazine.

55

5. Apparatus according to claim 1 having combined therewith a key-operated cam member for effecting movement of the pivoted printing member.

6. Apparatus according to claim 1 in which the pivoted printing member is capable of adjustment for the purpose of selecting a particular type character from a number of type characters of a single type-bar.

7. An apparatus as claimed in claim 1 including a movable carriage provided with segmentally formed members adapted to support the material to be printed upon, means for adjusting the position of said segmental members, arms secured upon said carriage, and an anvil strip pivotally mounted between said arms.

8. Apparatus as claimed in claim 1 including a movable carriage for supporting the material to be printed upon and means for actuating said carriage comprising a rocking plate carrying one fixed and one adjustable pawl, and a rack member on said carriage adapted to be engaged by said pawls, whereby the carriage is adapted to be spaced laterally through a definite predetermined distance.

9. In combination, a frame, a type magazine movably mounted in said frame, an actuating member for said magazine, cam levers having their cams engaging said actuating member, a plurality of keys arranged to strike said levers when either key is actuated in order to move the magazine to a position predetermined by the selected key, type bars supported by the magazine, a gripping lever adapted to grip the selected type bar, a paper carriage and means for swinging the last mentioned lever toward said carriage for causing the selected type bar to make an impression on the paper carried by said carriage.

In testimony whereof I have signed my name to this specification.

THOMAS WALTON.
